(57) **CLAIM**

The ornamental design for an electrical connector, substantially as shown and described.

DESCRIPTION

FIG. 1 is a front, top, and left side perspective view of an electrical connector showing our new design;

FIG. 2 is a front elevational view thereof shown with unclaimed environments;

FIG. 3 is a back elevational view thereof shown with unclaimed environments;

FIG. 4 is a left side elevational view thereof;

FIG. 5 is a right side elevational view thereof;

FIG. 6 is a top plan view thereof;

FIG. 7 is a bottom plan view thereof;

FIG. 8 is a back, bottom, and right side perspective view thereof;

FIG. 9 is a front, top, and left side perspective view thereof, shown with unclaimed environments in an exploded condition; and,

FIG. 10 is a front, top, and right side perspective view thereof, shown in use condition with unclaimed environments.

The broken line in the figure drawings is included for the purpose of illustrating unclaimed environment and forms no part of the claimed design.
